UNITED STATES PATENT OFFICE.

FRANK C. SOPER, OF CHICAGO, ILLINOIS, ASSIGNOR TO THE LUXFER PRISM PATENTS COMPANY, OF SAME PLACE.

DESIGN FOR A PRISM-LIGHT.

SPECIFICATION forming part of Design No. 27,974, dated December 7, 1897.

Application filed November 1, 1897. Serial No. 657,101. Term of patent 14 years.

To all whom it may concern:

Be it known that I, FRANK C. SOPER, a citizen of the United States, residing at Chicago, in the county of Cook and State of Illinois, 5 have invented a certain new and original Design for Prism-Lights, of which the following is a specification.

My invention relates to designs for prism-lights.

10 Figure 1 is a plan view of a prism-light embodying my design. Fig. 2 is a cross-section therethrough.

A is the body of the prism-light; B, one side thereof; C C, a series of prisms on the 15 opposite side of a certain size or depth; D D, a series of other prisms of a less size or depth. These prisms of different sizes or depths are

arranged with reference to each other on the prism side of the plate so as to form a figure or pattern.

The essential features of my design are found in a prism-light comprising a substantially flat body with prisms thereon, the prisms on one side being of different sizes or depths and arranged so as to form figures or patterns.

I claim—

20 A design for a prism-light, substantially as shown and described.

FRANK C. SOPER.
